UNITED STATES PATENT OFFICE.

JOHN ALBRECHT, OF KEWAUNEE, WISCONSIN.

AUTOMATIC NAILING DEVICE.

Application filed October 3, 1921. Serial No. 504,907.

To all whom it may concern:

Be it known that I, JOHN ALBRECHT, a citizen of the United States, and resident of Kewaunee, in the county of Kewaunee 5 and State of Wisconsin, have invented new and useful Improvements in Automatic Nailing Devices, of which the following is a description, reference being had to the accompanying drawings, which are a part of this 10 specification.

This invention relates to improvements in automatic nailing devices, particularly adapted for driving nails in boxes and the like.

15 The invention contemplates a driving hammer associated with a power driven reciprocably mounted member; and one of the objects of the invention is to provide a yieldable connection between the hammer and 20 the reciprocating member so that in the event a nail sticks in the nail chute or strikes some impenetrable substance the connection between the hammer and the reciprocating member will yield, and thus avoid breaking 25 the parts.

A further object of the invention is to 30 provide novel means for positioning the nails one at a time under the driving hammer and for guiding them while they are being driven said means preferably being in the 35 form of a yielding member provided with a main passageway for the driving hammer and a branch nail feed passageway leading into said main passageway, the lower portion 40 of said member being split on the axis of the main passageway into two parts and the two parts yieldably connected so that the lower portion of the main passageway may readily expand sufficiently to permit the nail heads to slip through, or, to permit the nail to bend or double over in case it should 45 strike some impenetrable substance.

A further object of the invention is to 50 provide novel means for guiding the nails and yieldingly moving the guiding means so that it will compensate for box parts of varying thicknesses to prevent the nails from being driven into the material beyond their heads.

55 In its preferred form the invention contemplates the provision of an upright supporting member to which a bracket is fixed in any desired manner, the supporting member having vertically extending guideways for a reciprocable cross head connected to the driving hammer; and a further object

of the invention is to provide means yieldably mounted on said bracket for positioning the nails under the hammer and for guiding them while being driven whereby 60 said means will readily accommodate itself to boxes varying somewhat in depth and width and thickness of material and to overlapped portions when nailing a round box. 65

The invention consists in the novel constructions, arrangements and devices to be hereinafter described and claimed for carrying out the above stated objects and such other objects as will appear from the following description of a certain preferred 70 embodiment illustrated in the accompanying drawings, wherein—

Fig. 1 is a front elevational view of an automatic nailing device embodying the principles of the invention; and Fig. 2 is a 75 sectional view taken on line 2—2 of Fig. 1.

Like characters of reference designate like parts in both views.

Referring now to the drawings, it will be seen that the nailing device is mounted upon a vertically extending supporting member 5 which forms part of a power driven machine having a table (not shown) on which the boxes to be nailed are placed.

A horizontally extending bracket member 6 is rigidly secured in any desired manner, in the present instance by a plurality of studs 7, to the supporting member 5. A nail positioning and guiding member 8 is yieldably mounted on the front side of the 90 bracket 6, the member 8 preferably having a rearwardly extending apertured lug 9 which normally projects through the upper portion of a slot 10 formed in the front side of the bracket. A vertically extending 95 rod 11 carried by the bracket 6 extends through the aperture in said lug, the member 8 being normally held in its uppermost position by means of an extension spring 12 coiled about the rod 11 and connected to a 100 portion of the bracket and to the upper side of the lug 9.

The member 8 is provided with a vertically extending main passageway 13 and a branch nail feed passageway 14 which leads 105 into the main passageway, substantially as shown in Fig. 2. That portion of the member 8 below the intersection of the two passageways is split on the axis of the main passageway so as to provide the parts 8^a and 110 8^b. The part 8^b is provided with one or more apertures which are in alignment with

internally threaded recesses provided in part 8^b so that threaded studs 15 may be inserted through the apertures and into the recesses, a spring 16 being coiled about each of the 5 studs and adapted to bear against the under side of the stud heads and the front side of the part 8^b, thus providing means yieldably connecting the parts 8^a and 8^b so that the 10 lower portion of the main passageway may expand sufficiently to permit the nail heads to slip therethrough. A nail chute 17 leads into the branch passageway 14.

The working end 18 of the driving hammer 19 is adapted to reciprocate in the main 15 passageway 13 and is approximately the same length of said passageway to drive the nails and the lower end of the hammer 19 at each downward reciprocation will strike the guiding member 8 and move it downwardly into engagement with the part being 20 nailed, and when said part is reached, any further movement of the parts which move the hammer will be taken up by means which will now be described. The hammer 25 20 is rigidly connected to a transversely extending yoke member 20 yieldably mounted on a cross head 21, the latter being reciprocally mounted on vertically extending guide- 30 ways 22 on the supporting member 5. The cross head is provided with a pair of forwardly extending apertured lugs 23. The yoke member 20 is provided with apertures which are in alignment with the apertures in the lugs 23. Rods 24 are inserted through 35 the aligned apertures in said yoke member and lugs, as shown in Fig. 1, the upper ends of said rods being connected to a driving means (not shown). The rods 24 are provided with collars 25 adapted to be drawn 40 up tightly against the under side of the respective lugs 23 and held in such position by nuts 26. Relatively stiff springs 27 are coiled about the respective rods, being interposed between the collars 25 and the yoke 45 member 20.

With a nailing device constructed as described, it will be seen that during normal 50 operation thereof the driving hammer which is substantially rigidly connected to the cross head will be moved downwardly to drive the nail and to move the guide member

8, against the tension of its spring 12, into engagement with the box part being nailed and any further movement of the cross head 21 will be taken up by the springs 27, thus 55 preventing the nail from being driven into the box part beyond its head. As the lower end of the guide member part 8^b is comparatively large the box part will not be injured by its engagement. If a nail should clog the 60 passageway 13 or should strike some impenetrable substance, the action of the springs 27 will also be overcome and while the cross head 21 will continue on its downward excursion, downward movement of the 65 driving hammer will be interrupted, so that there is no likelihood of any of the parts being broken. The lower portion of the main passageway 13 for the nails and driving hammer being expansible because of the 70 yielding connection of the part 8^b to the part 8^a there is little likelihood of the nails becoming wedged in the passageway 13 in such a manner as to make it difficult to 75 extricate them even though they do strike some impenetrable substance and bend or double over in the passageway.

In practice a plurality of the nailing devices are preferably arranged side by side so that several nails may be driven at one time, but since all the devices are of the same construction, such an arrangement will be clearly apparent from the foregoing description.

I claim:

In an automatic nailing device the combination of a reciprocating cross-head having a pair of overhanging apertured lugs, a hammer, a transversely extending member secured to said hammer and provided with apertures in alignment with the apertures in said lugs, bolts extending through the respective aligned apertures, said bolts being fixed to said lugs respectively, a collar on each of said bolts, and a spring surrounding each bolt interposed between the collar thereon and said member, for the purpose specified.

In testimony whereof, I affix my signature.

JOHN ALBRECHT.
